COOLING TOWER.

Application filed April 1, 1926. Serial No. 98,950.

This invention relates to cooling towers and is particularly applicable to forced draft cooling towers, although in certain of its aspects it is applicable to natural draft towers and to louver type towers.

Heretofore in the art, hot or warm liquids, such as the circulating water of steam engine condensers, have been cooled by subjecting the liquid to the action of cooling currents of air as it descends under the action of gravity in divided form. This cooling process has usually been carried out in a cooling tower in which the divided water descends within a vertical casing or enclosure. In so-called louver type towers, the side walls of the enclosure are provided with slats or louvers through which natural air currents may blow to effect cooling. Obviously, the cooling in such towers is very small upon a calm day and hence towers have heretofore been constructed in which the cooling currents of air are obtained by forced draft. Such towers consist essentially of a vertical casing within which the water descends, and a fan or the like to cause a draft of air to ascend through the tower. For high efficiency, it is necessary that the descending water and the ascending air currents be uniformly divided and distributed throughout the entire cross-section of the tower, and hence distributing means have been used in such towers in attempts to obtain such distribution. In the constructions of the prior art, however, the distribution of the air and water in the tower is not uniform and in many cases, the major portion of the air passes upward through one zone of the tower, while the major portion of the water passes downward through another zone of the tower. Prior art towers also have drawbacks in that the means employed to distribute the air and water in the tower offers quite high resistance to the air currents, and hence makes it necessary to expend a large amount of power in forcing the requisite quantity of air through the tower.

Prior art towers of the forced draft type have also had disadvantages due to the fact that the height of the tower has been increased by an amount at least equal to the diameter of the fan, which has usually been built into the base of the tower. Thus, the height of the tower has been correspondingly increased. Furthermore, prior art constructions have usually been such that

the height of the fan has been added to the total drop of the water, thus making it necessary to pump the water through this increased height in returning it to the steam engine condenser and then back to the top of the tower. Of course, the pumping through this additional height requires additional expenditure of power.

An object of the present invention is to provide an improved form of cooling tower in which the water and air is uniformly distributed and mixed throughout the entire cross-section of the tower.

Another object of the invention is to provide a cooling tower in which uniform distribution and mixture of the air and water is obtained without causing material obstruction to the flow of the air.

Another object of the invention is to reduce the height of forced draft cooling towers.

A further object of the invention is to reduce the pumping head caused by the fall of water through the cooling tower without substantial reduction of the amount of cooling obtained.

A still further object of the invention is to provide a highly effective forced draft cooling tower of simple and inexpensive construction and having low power requirements and operating costs.

In accordance with the above and other objects of applicant's invention, his preferred form of construction, as disclosed on the drawings, comprises a generally vertical casing sub-divided into a plurality of vertical flues. Spraying devices finely divide the water to be cooled and discharge it into the upper parts of these flues. The water descends by gravity through the flues which contain distributing devices that distribute and redistribute the water at definite points in its descent, thus securing fine subdivision and uniform distribution of the water throughout the entire cross-section of the casing for its entire fall. Near the bottom of the tower, the water is collected by collecting means from which it is delivered to a pump to be returned to the condenser and back to the top of the tower. This arrangement is such that the cooling tower has a vertically extending cooling zone which extends downwardly from the highest point to which the water is sprayed, to the collecting device positioned near the bottom of the casing.

The forced draft of air is delivered to the vertical casing immediately beneath the water collecting device, which is of such construction that it distributes the air and allows it to pass upwardly through the casing. The air in its ascent passes successively through the water distributing devices which also act as air distributing devices and insure uniform distribution of the air throughout the entire casing, as well as uniform mixture of the ascending air and descending water. The air is delivered to the vertical casing through a conduit leading from a suitable blower or the like that is spaced horizontally from the casing. This conduit is of such form that it decreases in height as it approaches the casing, thus making it possible to admit the air to the casing through a side wall opening that is of lesser height than the diameter of the fan. This construction correspondingly reduces the overall height of the tower.

Fig. 1 of the drawings is a diagrammatic elevation of the cooling tower having a portion of the side wall cut away to show the arrangement of parts within the tower.

Fig. 2 is a fragmentary perspective view of the interior of the tower, showing the arrangement of parts in one of the vertical flues.

Fig. 3 is a diagrammatic plan view of the tower shown in Fig. 1 with portions of the various distributing devices cut away to show the ones beneath.

Fig. 4 is a fragmentary diagrammatic plan view of the piping to the water sprays in the top of the tower.

Fig. 5 is a detailed sectional view taken on the line 5—5 of Fig. 1 to show the form of the air conduit.

Fig. 6 is a diagrammatic sectional view showing the manner in which the stream of air enters the casing and is distributed as it starts to ascend through the vertical casing.

Referring more particularly to Figs. 1, 2, and 3, the tower comprises a rectangular vertical casing 1 sub-divided into four vertical flues by partitions 2, 3, 4, and 5, which extend from a point near the bottom of the casing to within a short distance of the top of the casing. Water to be cooled is delivered into the upper portion of each of the four vertical flues through suitable spray nozzles 7, which receive the water from branch pipes 8 and spray it upwardly in finely divided form. The water descends through successive distributors denoted as a whole by A, B, and C. Each of these distributing devices consists of a horizontally arranged series of inclined slat-like members 10, which may be secured in place in any suitable manner. Formed on the lower edge of each of the slat-like members 10 is a shallow trough 11 from which depends a short strip of metal gauze 12. The arrangement of the slat-like members is such that the upper edge of one member is directly over the lower edge of the adjacent member so that all of the water is intercepted by the slat-like members as it falls. The water from the sprays is intercepted by the slat-like members of distributor A and collected in the shallow troughs 11 from which it overflows down to the strips of metal gauze 12 from which it drips off in finely divided form.

As the water descends, it is correspondingly intercepted and redistributed by distributors B and C. At the bottom of the cooling zone, the water is intercepted and collected by a collector-distributor denoted as a whole by D. This collector comprises a horizontally arranged series of slat-like members 14, each of which has a pair of troughs 15 and 16 formed upon its upper face. The water collects in these troughs from which it is discharged into suitable carry-off troughs 17 and delivered to a collector trough 18, which is connected with a suitable pump 19.

The bottom of the vertical casing is closed by a suitable inclined plate 21, which forms a wedged-shaped space beneath the collector-distributor D. The collector-distributor corresponds to one of the diverging faces of the wedges and the plate 21 is the opposite diverging face of the wedge. A current of air is delivered to the vertical casing through an opening in the side wall of the casing at a point which corresponds to the base of the wedged-shaped space beneath the air distributor. The air enters the casing in a direction parallel to the inclined plate 21, and as shown in Fig. 6, successive layers of the current of air strike the inclined members of the collector-distributor D and are deflected upwardly into the tower in such a way as to produce uniform distribution of the air. It is seen that the device D collects the water and distributes the air. Hence it has been denominated a "collector-distributor". As shown by the arrows in Fig. 1, the air passes upwardly through distributors C, B, and A, which distribute and redistribute it as it ascends, thus maintaining uniform distribution of the air throughout the entire cross-section of the tower and causing uniform mixture of the ascending air and the descending water. It will be noted that the slat-like members in collector-distributor D run perpendicularly to those in distributor C which in turn are perpendicular to those in distributor B, and so on. This arrangement produces very uniform distribution and intimate mixture of the air and water. Furthermore, it will be noted that as the air leaves a distributor, it is moving diagonally upward so that it cuts across the path of the descending water, thus causing the current of air to be very effective in cooling the water.

The current of air is supplied to the vertical casing through a conduit 25, which leads from a suitable fan or blower 26. By reference to Fig. 5, it will be noted that this conduit is of such form that it is of substantially uniform cross-sectional area throughout its length, but at the fan end, it is circular to correspond to the shape of the fan, while as it approaches the vertical casing 1 of the cooling tower, it continually decreases in height so that the conduit at the cooling tower end is of much less height than it is at the fan end. Accordingly, the fan is mounted so that a part of its sweep is above the distributor-collector D and hence the fan adds only a comparatively small amount to the over-all height of the cooling tower. The height of the vertical casing at one side is not increased at all by reason of the fan, while at the other side, it is only increased a height equal to the height of the base of the wedged-shaped space beneath the distributor-collector D, which is much less than the total diameter of the fan.

It is seen that the construction is one in which the distributors A, B, C, and D offer only an exceedingly small resistance to the ascending air currents, thus economizing in the power required to drive the fan. Furthermore, the cooled water is collected as soon as it reaches the bottom of the cooling zone established by the collector-distributor D and hence in returning the water to the condenser and back to the top of the cooling tower, it is only necessary to pump through a relatively small pumping head indicated in Fig. 1. This effects decided economy in the power required to drive the water pump.

To prevent any of the water from being blown away by the wind as it is sprayed up, the casing 1 extends a short distance above the sprays 7.

To prevent any water from running to the fan casing which through leakage or other causes might descend to the wedge shaped space beneath the distributor D, a suitable drain 28 is provided. This drain may be provided with a water seal 33 to prevent any of the air delivered to the wedge-shaped space from passing out through the drain pipe.

The invention has been illustrated diagrammatically and hence it is to be understood that any suitable mechanical construction can be used in building and supporting the vertical casing, mounting the distributors A, B, C, and D, the fan 26, the pump 19, etc. The construction is one which can be readily built from standard plates, angle irons, I beams, channel beams, etc. The distributors and other parts with which the water comes in contact may be formed of any suitable corrosive resisting material.

It is realized that the present invention

may be employed in forms other than those particularly disclosed and hence the disclosure is to be considered as illustrative and not as limiting. Cooling towers are used primarily for cooling the water from steam engine condensers and hence the invention has been described in this connection, and for convenience the term "water" has been used to designate the liquid to be cooled. However, it is to be understood that the invention is not limited to use for cooling water, but that it can be used for cooling any liquid.

Having thus described my invention, what I claim is:—

1. A cooling tower comprising a substantially vertical casing, an air distributor traversing said casing, means forming a wedge-shaped space beneath the distributor, means to finely divide water to be cooled and supply it to the space within the casing at a point above the air distributor, means to collect the water at the level of the air distributor, means to supply a stream of air to the wedge-shaped space through the base portion thereof, and drain means to carry off any moisture which may descend to the wedge-shaped space.

2. A cooling tower comprising a vertical casing; a plurality of vertically spaced air and water distributors traversing said casing, said distributors comprising substantially horizontally arranged series of inclined slat-like members; vertical partition means dividing said casing into a plurality of flues; means to discharge water to be cooled at a level above the distributors, whereby the water passes downward through the distributors under the action of gravity; and means to force a current of air upward through the distributors, part of said current of air passing through each of the flues and each part passing out to the atmosphere upon reaching the top of the casing.

3. A cooling tower comprising a vertical casing; a plurality of vertically spaced air and water distributors traversing said casing, the lowermost distributor being adjacent the bottom of the casing and each distributor comprising a substantially horizontally arranged series of inclined slat-like members; means to discharge water to be cooled at a level above the uppermost distributor, whereby the water passes downward under the action of gravity; means to collect the water at the level of the lowermost distributor; and means to force a current of air upward through the distributors.

4. A cooling tower comprising a vertical casing; a plurality of vertically spaced air and water distributors traversing said casing, each distributor comprising a substantially horizontally arranged series of inclined slat-like members which members are provided at their lower edges with troughs,

the troughs of the lowermost distributor being arranged to be drained and the troughs of the other distributors being arranged to collect the water and cause it to overflow from the troughs; means to discharge water to be cooled at a level above the uppermost distributor, whereby the water passes downward through the distributors under the action of gravity and overflows from the distributor troughs which are above the lowermost distributor, and means to force a current of air upward through the distributors.

5. A cooling tower comprising a vertical casing, a plurality of vertically spaced air and water distributors traversing said casing, said distributors comprising series of inclined slat-like members, troughs on the bottoms of said slat-like members, and strips of gauze depending from said troughs; means to discharge water to be cooled above the series of distributors whereby the water passes downward through the distributors under the action of gravity, and means to force a current of air upward through the distributors.

6. In a cooling tower, a distributor comprising a horizontally arranged series of inclined slat-like members, a trough on the bottom of each slat-like member adapted to collect water and allow it to overflow, and a strip of gauze depending from each slat-like member.

7. In a substantially horizontal cooling tower, a water collection unit comprising a series of inclined slat-like members arranged to intercept water descending through the tower, means forming troughs on the faces of the slat-like members to receive the intercepted water, and at least one carry off trough positioned to receive water from the ends of the troughs on the slat-like members.

8. A cooling tower comprising a substantially vertical casing; a substantially horizontal collector-distributor traversing said casing, said collector-distributor comprising a series of inclined slat-like members arranged to distribute air delivered to the cas-

ing beneath the collector-distributor and to intercept water descending through the tower, and means forming troughs on the faces of the slat-like members; at least one carry off trough positioned to receive water from the ends of the troughs on the slat-like members; means forming a substantially wedge-shaped space beneath the collector-distributor, and means to supply a stream of air to the wedge-shaped space through the base portion thereof.

9. A cooling tower comprising a substantially vertical casing; means dividing said casing into a plurality of flues, a substantially horizontal collector-distributor traversing said flues collectively, said collector-distributor comprising a series of inclined slat-like members arranged to distribute air delivered to the casing beneath the collector-distributor and to intercept water descending through the tower, and means forming troughs on the faces of the slat-like members; at least one carry off trough positioned to receive water from the ends of the troughs on the slat-like members; means forming a substantially wedge-shaped space beneath the collector-distributor; and means to supply a stream of air to the wedge-shaped space through the base portion thereof.

10. A cooling tower comprising a vertical casing; a plurality of vertically spaced air and water distributors traversing said casing, each distributor comprising a substantially horizontally arranged series of inclined slat-like members with the members of one distributor perpendicular to the members of the next distributor; means to discharge water to be cooled at a level above the uppermost distributor, whereby the water passes downward through the distributors and falls freely through the spaces between the distributors; and means to force a current of air upward through the distributors; said construction causing the air to cut diagonally across the path of the descending water as the air leaves the distributors.
